UNITED STATES PATENT OFFICE.

JOHN T. TRUITT, OF ST. LOUIS, MISSOURI.

COLLAR-IRONING APPARATUS.

1,069,988.

Specification of Letters Patent. Patented Aug. 12, 1913.

Application filed October 21, 1912. Serial No. 726,904.

To all whom it may concern:

Be it known that I, JOHN T. TRUITT, a citizen of the United States of America, residing at St. Louis, in the State of Missouri, have invented certain new and useful Improvements in Collar-Ironing Apparatus, of which the following is a full, clear, and exact description, reference being had to the accompanying drawings, forming a part of this specification.

My invention relates to an apparatus for ironing personal apparel collars of the kind known as "turn over" collars, and the apparatus is one intended particularly for ironing the tops or folds of the collars of the type alluded to.

Various attempts have been made to produce means by which the folds of turn over collars may be satisfactorily ironed in a manner to render the folds perfectly smooth and uniform when the collar has been ironed, and also in a manner to avoid cracking or breaking of the starched and stiff fabrics in the collars. These attempts have, however, so far as I am aware, been only partially successful; and it is the object of my invention to produce an apparatus by which the operations of ironing the top folds of turn over collars may be carried out with a maximum of perfection.

Figure I is a top or plan view of my apparatus, with portions broken away to afford views of the parts beneath them. Fig. II is an inverted plan view of the holder occupied by the smoothing irons of my apparatus, and the smoothing irons therein, a portion of said holder and one of the smoothing irons being shown in horizontal section. Fig. III is an enlarged horizontal section taken through a fragment of the smoothing iron holder and one of the smoothing irons, and also through fragments of the collar holder and the collar thereon in position in said smoothing iron to illustrate the relative position of the parts during collar ironing operations. Fig. IV is a view partly in side elevation and partly in vertical section of my apparatus. Fig. V is a perspective view of one of the smoothing irons. Fig. VI is a perspective view of a fragment of the collar holder, and one of the clips carried thereby illustrated as it appears in retaining one of the tongues of the collar when the collar is in position on

the holder. Fig. VII is a horizontal section taken on the line VII—VII, Fig. IV.

In the drawings:—1 designates the base of my apparatus, which may be maintained upon any suitable support, and is surmounted by a bracket arm 2, having a horizontal member 3, terminating in a head 4. The bracket arm 2 serves as a support for a holder A, in which is mounted a plurality of smoothing irons to be hereinafter particularly described, and said head is preferably connected to said bracket arm by a vertical stem 5 arranged in the head 4 of the bracket arm and, if desired, adjustably held therein by a set screw 6, (see Fig. IV).

B designates a collar holder, which is of cup-shape, and has a tapering rim 7 on which a turn over collar may be positioned preparatory to ironing its top fold. It is well to here state that the sides of the collars intended to be operated upon in my apparatus are thoroughly ironed before they are placed upon the collar holder B, except in so far as the folds of the collars are concerned; and these folds are moistened previous to being ironed by the use of my apparatus.

In order that the collar holder B may be moved to and from a position beneath the smoothing iron holder A, to permit the desired ironing operations and the mounting of the collars on the collar holder, I mount the collar holder on a supporting arm 8, which is pivotally fitted to a post 9 extending upwardly from the base 1. The portion of said supporting arm immediately surrounding the post 9 is provided with a segment shaped slot 10, and the post is provided with a stop pin or stud 11, arranged in said slot to serve as a means for limiting the movement of the supporting arm on its pivot. It will be apparent that one of the end walls of said slot may be so positioned that the movement of the supporting arms will be stopped when the collar holder is directly beneath and concentric with the smoothing iron holder A.

The collar holder B is intended to be oscillated when it is positioned beneath the smoothing iron holder, and to permit of such movement of the collar holder, it is provided with a depending vertical stem 12, that is loosely arranged in the free end of the supporting arm 8, and extends beneath said

arm. Oscillatory movement may be imparted to the collar holder by any suitable means, the means I have shown for this purpose comprising the following elements.

- 5 13 is an operating shaft that may be driven in any suitable manner. This shaft is supported by any suitable means and is preferably located above the pivot of the supporting arm 8. The shaft is provided
10 with a crank arm 14 that carries a swivel 15 to which is attached a connecting rod 16. The connecting rod is pivoted to a swivel 17 carried by the collar holder B. It will be apparent that when the operating shaft 13
15 is rotated, its crank arm will, by traveling in a circular path, impart a reciprocating movement to the connecting rod 16, and the latter will in turn impart an oscillatory movement to the collar holder.
- 20 When the parts are arranged as shown in the drawings, it is necessary to move the collar holder vertically relative to the smoothing iron holder A, in order that the desired ironing operation may take place, and the desired movements of this kind may be obtained by the device shown in Fig. IV, which is coöperable with the stem 12 of the collar holder. This device comprises a double armed lever 18 fulcrumed at 19. One
25 arm of this lever is located beneath the stem of the collar holder, and the other arm of the lever is engaged by a D-shaped cam 20 on a shaft 21, which may be operated in any suitable manner. It will be obvious that when
30 the cam 20 is rotated, its curved face will, by operating against the lever 18, act to depress the arm of the lever engaged thereby and elevate the other arm of the lever, with the result of causing it to elevate the collar holder, and further obvious that when the flat face of the cam comes into contact with the lever 18, the arm of said lever that engages the stem of the collar holder will move to its lowered position to permit the descent
35 of the collar holder.

I now come to the important features of my present invention, namely, the ironing elements to which the parts of the apparatus heretofore described are subsidiary. It will
40 first be noted that the iron holder A is chambered to provide a heat receiving compartment 22 therein, into which heating medium may be introduced. The iron holder is preferably heated by the use of steam; and to provide for its being so heated, I connect to it steam conducting pipes 23, one of which may serve as an inlet pipe, and the other of which may serve as an outlet pipe. In the iron holder A and extending upwardly from
45 its lower face is a groove 24, with which the rim 7 of the collar holder B is concentric when said collar holder is positioned beneath the iron holder, thereby providing for said rim and the collar thereon entering into said groove when the collar holder is moved

to the iron holder. In the iron holder, coincident with the groove 24, are bores 25 arranged in circular series, and in close juxtaposition.

26 designates cylindrical smoothing irons arranged in the bores 25 of the iron holder. These smoothing irons are provided with upwardly extending stems 31, which project through the top of the iron holder above the bores 25, and protrude beyond the top of said holder, as most clearly seen in Fig. IV. The stems of the smoothing irons are surrounded by helical springs 32, located between the bodies of the irons and the tops of the bores 25, by which the smoothing irons are yieldingly depressed into lowered positions, the said springs, however, yieldingly permitting upward movement of the smoothing irons for a purpose that will hereinafter fully appear.

In the body of each smoothing iron 26 is a slot 27, this slot being preferably of triangular shape, as most clearly seen in Fig. V. The slots 27 receive screws or pins 33 that extend into the bores 25 from the outer wall of the smoothing iron holder A, and serve to limit the longitudinal play of the smoothing irons and also to readjust said smoothing irons, when rotated, as will hereinafter fully appear.

Each smoothing iron is bifurcated at its lower end, providing a groove 28, which extends transversely of the smoothing iron, and two legs 29 and 30, which, as well as the base of the groove, furnish collar ironing faces, when the smoothing iron is operated against the fold of a turn over collar that is to be ironed. The groove 28 in each smoothing iron is of greater width than the thickness of the fold of a collar when in position on the collar holder B, in order that the smoothing iron may partake of a rotative movement while the fold of the collar is present in such groove.

34 designates springs by which the smoothing irons 26 are subjected to partial rotation for a purpose to be presently made clear. These springs, as illustrated in the drawings are of S-shape, and each spring extends through the upwardly projected end of the stem of the smoothing iron it is to impart partial rotation to, while its other end embraces the next adjacent smoothing iron stem. Springs of this kind, arranged as mentioned, furnish simple and efficient means for partially rotating the smoothing irons, and it is obvious that other types of springs, or equivalent means, might be utilized for the same purpose.

In the practical use of my ironing apparatus, a collar of which the fold is to be ironed is placed on the rim 7 of the collar holder B and secured in place by suitable means, such as the clips shown; and the folded collar having been moistened, either

before or after the mounting on the collar holder, is ready to be ironed. The collar holder B is next elevated to the smoothing iron holder, and an oscillatory movement is imparted thereto by the means provided for such movements of the collar holder.

One of the clips for holding the collar to the work holder shown in the drawings is a tongue rigidly secured to the rim of the work holder and having at its upper end an outturned lip adapted to extend over the tabs of the collars to be ironed, as seen in Fig. VI. The other clip has a lip which overlies the other tab of the collar to be ironed, this clip being adjustably secured to the rim of the work holder, in order that it may be slid thereon to place its lip over the tab that receives it after the collar has been fitted to the work holder, with one of its tabs held by the first mentioned clip.

When the collar on the holder B is presented to the iron holder, the fold of the collar enters the grooves 28 in the plurality of smoothing irons 26, and said smoothing irons are moved longitudinally against the action of the springs 32, with a constant but yielding pressure exerted by the irons against the fold of the collar. It will be apparent that when the collar is thus presented to the smoothing irons, the top of its fold seats against the base faces of the grooves 28 and, therefore, this portion of the fold is effectually ironed, while the collar holder B is in its elevated position and is subjected to oscillatory movement. Upon the upward or longitudinal movement of the smoothing irons 26, said irons are so adjusted that the pins 33 become positioned in the wider lower portions of the slots 27 in the irons and, as a consequence, said irons are permitted to partake of a partial rotation they are not susceptible of when the pins occupy the upper ends of said slots. The springs 34 are, therefore, permitted to impart a partial rotation to the smoothing irons, in consequence of which the inner ironing faces of the legs 29 and 30 of the smoothing irons are presented to the sides of the fold of the collar, and yieldingly held thereagainst while the collar is moved through the grooves in the irons. As a result, the sides of the fold of the collar are effectually ironed at the same time that the top of such fold is being ironed.

When the collar holder is withdrawn from the smoothing iron holder of my apparatus, the springs 32 act to return the smoothing irons to their lowered positions and, during this movement, the pins 33 re-enter the narrow upper ends of the slots 27 in the smoothing irons and, by so doing, act to re-rotate the irons to their normal positions so that the grooves therein are properly adjusted to permit the ready entrance of the next collar mounted on the collar holder into

the series of smoothing irons, preparatory to the next ironing operation similar to that already described.

I claim:

1. An ironing apparatus comprising a work holder, a smoothing iron holder, a bifurcated smoothing iron rotatable in said smoothing iron holder, one of said parts being movable relative to the other to cause said smoothing iron to straddle said work holder, means for imparting a partial rotation to said smoothing iron while straddling said work holder, and means for re-rotating said smoothing iron to normal position.

2. An ironing apparatus comprising a work holder, a smoothing iron holder, a bifurcated smoothing iron rotatable in said smoothing iron holder, one of said parts being movable relative to the other to cause said smoothing iron to straddle said work holder, means for imparting a partial rotation to said smoothing iron while straddling said work holder, and a slot and pin connection between said smoothing iron and smoothing iron holder whereby said smoothing iron is returned to normal position.

3. An ironing apparatus comprising a work holder, a smoothing iron holder, a bifurcated smoothing iron rotatable in said smoothing iron holder, one of said parts being movable relative to the other to cause said smoothing iron to straddle said work holder, means for yieldingly resisting longitudinal movement of said smoothing iron when it is presented to said work holder, means for imparting a partial rotation to said smoothing iron while straddling said work holder, and means for returning said smoothing iron to normal position.

4. An ironing apparatus comprising a work holder, a smoothing iron holder, a bifurcated smoothing iron rotatable in said smoothing iron holder, one of said parts being movable relative to the other to cause said smoothing iron to straddle said work holder, means for yieldingly resisting longitudinal movement of said smoothing iron when it is presented to said work holder, and a spring for imparting a partial rotation to said smoothing iron after it is presented to said work holder.

5. An ironing apparatus comprising a work holder, a smoothing iron holder, a bifurcated smoothing iron rotatable in said smoothing iron holder, one of said parts being movable relative to the other to cause said smoothing iron to straddle said work holder, means for yieldingly resisting longitudinal movement of said smoothing iron when it is presented to said work holder, a spring for imparting a partial rotation to said smoothing iron after it is presented to said work holder, and means whereby said smoothing iron is re-rotated.

6. In a collar ironing apparatus, a collar holder, a smoothing iron holder, a plurality of grooved smoothing irons rotatably mounted in said iron holder, means for imparting a partial rotation to said smoothing irons, and means for re-rotating said smoothing irons to normal position.

7. In a collar ironing apparatus, a collar holder, a smoothing iron holder, a plurality of smoothing irons slidably and rotatably mounted in said holder, means for imparting

partial rotation to said smoothing irons, each smoothing iron being provided with a tapering slot, and means mounted in said iron holder entering into the tapering slots in said smoothing irons for restoring the smoothing irons to normal position after they have been partially rotated.

J. T. TRUITT.

In the presence of—
A. J. McCUALEY,
E. B. LINN.
